CLAIM

The ornamental design for a wing dipping bowl, as shown and described.

DESCRIPTION

FIG. 1 is a front perspective view of a wing dipping bowl set inside a block holder in accordance with one implementation; FIG. 2 is a front, right perspective view thereof; FIG. 3 is a back, left perspective view thereof; FIG. 4 is a top plan view thereof; FIG. 5 is a front elevational view thereof; FIG. 6 is a back elevational view thereof; FIG. 7 is a right elevational view thereof; FIG. 8 is a left elevational view thereof; FIG. 9 is a bottom plan view thereof; FIG. 10 is a front perspective view of a wing dipping bowl set inside a block holder in accordance with another implementation; FIG. 11 is a front, right perspective view thereof; FIG. 12 is a back, left perspective view thereof; FIG. 13 is a top plan view thereof; FIG. 14 is a front elevational view thereof; FIG. 15 is a back elevational view thereof; FIG. 16 is a right elevational view thereof; FIG. 17 is a left elevational view thereof; and, FIG. 18 is a bottom plan view thereof.

The broken lines, including the broken lines showing environment in the drawings, are included for illustrative purposes only and form no part of the claimed design. The appearance of any portion of the bowl between the break lines in the figures forms no part of the claimed design.
